UNITED STATES PATENT OFFICE.

JULIUS BRENZINGER, OF MOUNT VERNON, NEW YORK, ASSIGNOR TO SANITARY CAN MACHINERY COMPANY, OF ELLSWORTH, MAINE, A CORPORATION OF MAINE.

CAN-HEADING MACHINE.

No. 821,605.

Specification of Letters Patent.

Patented May 29, 1906.

Application filed June 15, 1905. Serial No. 265,407.

To all whom it may concern:

Be it known that I, JULIUS BRENZINGER, a citizen of the United States, residing at Mount Vernon, Westchester county, State of New York, have invented new and useful Improvements in Can-Heading Machines, of which the following is a specification.

This invention relates to a machine for securing can-heads to can-bodies of round, square, or other shape by means of a double seam.

The machine is so constructed that the seaming-rollers will accurately follow the contour of the can to be closed, and thus form a perfect seam.

In the accompanying drawings, Figure 1 is a side elevation of my improved can-heading machine with some of the parts omitted; Fig. 2, a front elevation of part of the machine; Fig. 3, a detail horizontal section, partly broken away, of the seaming-levers; Fig. 4, a side elevation thereof. Figs. 5 and 6 are details of the two parts of the seaming-lever; Fig. 7, a side view of the clutch and brake operating cam and adjoining parts; and Fig. 8, a detail of part of the can-body, showing it engaged by the platform and chuck.

The letter A indicates the frame of the machine, and a is the power-shaft, which transmits motion by pulley a' and belt a² to a clutch-pulley b', loosely mounted upon a work-shaft b. To the latter is affixed a sprocket-wheel b², which transmits motion by an endless chain c, running over idlers c' c², to a sprocket-wheel d', fast on a vertical worm-shaft d. Below sprocket-wheel d' there is mounted upon shaft d a second sprocket-wheel d², which transmits motion by chain e, running over idlers e' e², to a sprocket-wheel f'. This wheel is rotatably mounted upon a vertically-movable rod f, which is in vertical alinement with shaft b. Chain c and sprocket-wheels b² d' correspond in size to chain e and sprocket-wheels f' d², so that sprocket-wheels b² and f' will rotate with the same speed and their relative positions will always remain the same. Sprocket-wheel f' forms part of a platform f², provided with a raised central section f³, which corresponds in shape to that of the can-body B to be headed and is adapted to enter a recess in the can-bottom B', Fig. 8. Rod f is guided in bearings A' A² of frame A and may be raised and lowered so as to bring the

can-body into or out of engagement with the seaming means hereinafter described.

For operating rod f a hand-lever g, influenced by a spring g', is provided, which is connected by a link g² to a collar g³, loosely fitted upon the rod. Upon collar g³ are supported a pair of cushions g⁴, that bear against a collar f⁴, secured to rod f. By depressing handle g, rod f and platform f² will be raised, while upon releasing the handle the rod and platform will be lowered by spring g'.

For seaming the can and operating the seaming means the following construction has been devised: Worm-shaft d is provided with a worm d³, engaging a worm-wheel h' of a cam-shaft h. This shaft is provided with a cam h² for operating the clutch and brake in manner hereinafter described and with a pair of cams h³ h⁴ for operating the seaming-levers. The drawings show two seaming-levers; but as their operating means are alike the same description will apply to both. Each cam h³ is engaged by a cam-roller i', journaled in the lower end of a vertically-reciprocating spindle i. The latter is guided in bearings A³ A⁴ and is provided with a laterally-projecting pin i², engaging a vertical slot i³ of a guide-plate i⁴ to prevent rotation of the spindle. Upon spindle i oscillate an upper or guide lever j and a lower or seaming-lever which is composed of two sections k k'. Such levers having, therefore, coincident pivots. The guide-lever j is provided with two hubs or eyes j' j², connected by a bar j³, so as to increase the bearing of the lever and prevent it from tilting. The free end of lever j carries a guide-roller j', which travels in a groove l' of a cam-disk l, fast on shaft b. The groove l' corresponds in form to that of the can to be headed. The lower section of disk l constitutes a chuck l², which is adapted to enter the recessed cover B² of the can B, Fig. 8, and thus hold the can in position during the seaming operation. The inner section k of the seaming-lever carries at its free end the seaming-roller K, while its reduced rear portion k² is flanked by flanges k³, extending inwardly from the outer lever-section k'. The sections k k' are yieldingly connected by a clamp-screw k⁴, tapped into lever k, and by a pressure-screw k⁵, tapped into lever k'. Between screw k⁵ and lever k a cushion k⁶ is interposed, which permits the roller K to ride

freely over the side seam of the can-body. The lever j bears with its upper side against bearing A^3 , while the lever-section k' is supported upon a fixed abutment A^5 . In this way the levers j and k' are prevented from partaking in the axial movement of spindle i . The roller j^4 by engaging groove l swings the free end of lever j , as well as of lever k' , to assume a position corresponding to the contour of the can-body. In addition to this movement the lever k' receives a further inward movement whereby the seaming-roller K is pressed against the can-body to perform the seaming operation. For this purpose there is secured to lever j by nut j^5 a downwardly-projecting pin or abutment j^6 , which may serve as a pivot for a roller j' , having a circumferential groove j^8 . This groove is engaged by the outer face of a horizontally-movable wedge k^6 , slideable within a longitudinal groove k^7 of lever-section k' . To wedge k^6 is pivoted at m' one end of a link m , coupled by pin n' to a second link n , the whole constituting a toggle. Link n is pivoted to lever-section k' , as at n^2 . Upon pin n' is free to turn a roller o , which is adapted to ride upon a disk o' , rigidly secured to spindle i . Levers j and k' are connected by a spring p , engaging pin j^8 of lever j and a pin k^8 of lever-section k' . The rotation of cam h^3 will cause a vertical reciprocating movement of spindle i and disk o' . When said disk is raised, it will lift roller o , and thereby distend toggle-joint $m n$, thus causing the wedge k^6 to be advanced. (See arrow in Fig. 3.) When disk o' is lowered, it will allow toggle-joint $m n$ to be contracted, thereby retracting wedge k^6 . The wedge k^6 in advancing will crowd lever k' away from roller j' , so as to press seaming-roller K against the can-body and perform the seaming operation. When the disk o' is lowered, the wedge k^6 is retracted to permit spring p to swing roller K off the can-body B . The cams h^3 h^3 are so set that the rollers K K are consecutively brought into engagement with the can to be headed. In this way the first roller starts the seaming operation, while the second roller completes the same, as usual.

Hand-lever g , which serves to raise platform f^2 , also serves to start the machine and to open the brake in the following manner: Lever g is provided with a depending arm g^5 , to which is pivoted one end of a rod p , the other end of which is connected to an elbow-lever r , pivoted to frame A at r' . To the lower arm of lever r is journaled at r^2 a roller r^3 , engaging cam h^2 of shaft h . The upper arm of lever r is by rod s connected to a double lever t , pivoted at t' to frame A . This lever engages a groove b^3 of the movable member b^4 of clutch $b' b^4$, which may be of any suitable construction. Lever t is by rod u further connected to a brake-lever v , pivoted at v' to frame A and influenced by a spring v^2 . Lever v engages the brake-shoe

w' of a brake-disk w , fast on shaft b . It will be seen that by depressing hand-lever g roller r^3 will be lifted out of notch h^4 of cam h^2 . Further, the clutch member b^4 will be lowered to close clutch $b' b^4$, and thus start the machine, while the brake $w w'$ is simultaneously opened by the engagement of notch v^3 of lever v with the tailpiece w^2 of brake-shoe w' . When the machine is started, roller r^3 will ride along the convex edge h^5 of cam h^2 , and thus prevent the clutch from opening, even after hand-lever g has been released. After cam-shaft h has made a complete rotation roller r^3 will enter recess h^4 by the combined action of the springs $g' v^2$. In this way lever r will tilt levers g , t , and v to lower platform f^2 and open clutch $b' b^4$ and also to set the brake.

It will be seen that with my machine the guide-levers j and seaming-levers k k' turn on coincident pivots, so that the seaming-rollers and guide-rollers describe an arc struck off from a common center and by an equal radius. The result is that the seaming-rollers will be so set as to conform accurately to the contour of the can and form a perfect seam, which action is not attainable when the guide-levers and the seaming-levers turn on differently-positioned pivots.

What I claim is—

1. In a can-heading machine, a guide-lever, a seaming-lever, a spindle on which both levers are fulcrumed, a seaming-roller carried by the seaming-lever, and means for operating the levers, substantially as specified.
2. In a can-heading machine, a guide-lever and a seaming-lever having coincident pivots, a cam engaged by the guide-lever, and means for operating the seaming-lever, substantially as specified.
3. In a can-heading machine, a guide-lever, a seaming-lever, a spindle on which both levers are fulcrumed, a cam engaged by the guide-lever, and a horizontally-slideable wedge adapted to operate the seaming-lever, substantially as specified.
4. In a can-heading machine, a guide-lever, a seaming-lever, a spindle on which both levers are fulcrumed, a wedge between the levers, and means for operating the wedge, substantially as specified.
5. In a can-heading machine, a guide-lever and a seaming-lever having coincident pivots, an abutment on one of said levers, and a wedge between said abutment and the other lever, substantially as specified.
6. In a can-heading-machine, a guide-lever and a seaming-lever having coincident pivots, a pin on one of said levers, a roller on said pin, and a wedge between said roller and the other lever, substantially as specified.
7. In a can-heading machine, a guide-lever and a seaming-lever having coincident pivots, an abutment on one of said levers, a wedge between said abutment and the other lever, substantially as specified.

- lever, and means for reciprocating the wedge, substantially as specified.
8. In a can-heading machine, a guide-lever, a seaming-lever, a spindle on which both levers are fulcrumed, an abutment on one of said levers, a wedge between said abutment and the other lever, and means for reciprocating the wedge, substantially as specified.
9. In a can-heading machine, a guide-lever, a seaming-lever, a wedge between the levers, a toggle-joint for operating the wedge, a roller on the toggle-joint, and a vertically-movable disk engaging the roller, substantially as specified.
10. In a can-heading machine, a guide-lever, a seaming-lever composed of two sections and having a pivot coincident with the guide-lever, a cushion between the seaming-lever sections, and a seaming-roller carried by one of said sections, substantially as specified. 15
